(57) **CLAIM**

I claim the ornamental design for a bicycle, as shown and described.

DESCRIPTION

FIG. 1 is a left side elevational view of my bicycle, showing my new design;

FIG. 2 is a right side elevational view of the design of FIG. 1;
FIG. 3 is a front elevational view of the design of FIG. 1;
FIG. 4 is a back elevational view of the design of FIG. 1,
FIG. 5 is a top elevational view of the design of FIG. 1; and,
FIG. 6 is a bottom elevational view of the design of FIG. 1.
Any broken line illustration of environmental structure in the drawings is not part of the design sought to be patented.
